[57] CLAIM

The ornamental design for a wheel chair tray, as shown and described.

DESCRIPTION

FIG. 1 is a top plan view of a wheel chair tray showing my new design;

FIG. 2 is a bottom plan view thereof; and

FIG. 3 is a front elevational view thereof.

The side and rear edges of the tray are understood to be substantially flat and unornamented.

FIG. 1

FIG. 2

FIG. 3
